(57) **CLAIM**

The ornamental design for a shaving razor tray as shown and described.

DESCRIPTION

FIG. 1 is a top perspective view of a design of a shaving razor tray of the present invention;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is bottom perspective view thereof.

The broken lines shown illustrate portions of the shaving razor tray and form no part of the claimed design.

1 Claim, 6 Drawing Sheets
